UNITED STATES PATENT OFFICE.

LORENCE ERICKSON, OF DAWSON, MINNESOTA.

TAILOR'S KIT.

1,387,970.

Specification of Letters Patent. Patented Aug. 16, 1921.

Application filed March 1, 1921. Serial No. 448,857.

To all whom it may concern:

Be it known that I, LORENCE ERICKSON, a subject of the King of Sweden, who have declared my intention to become a citizen of the United States, residing at Dawson, in the county of Lac qui Parle and State of Minnesota, have invented a new and useful Tailor's Kit, of which the following is a specification.

10 My invention relates to mechanics' tool holding cabinets, and owing to its peculiar design it may be termed a tailor's kit, since the object is to provide a tailor with a very convenient device for holding tools, chalk, 15 threads, buttons, needle cushion, etc., in ready position for use.

In the accompanying drawing:

Figure 1 is a front elevation of my device.

Fig. 2 is a side elevation of Fig. 1.

20 Fig. 3 is a rear elevation of the device on a reduced scale.

Fig. 4 is a section on line 4—4 of Fig. 1 on a reduced scale.

Fig. 5 is an end elevation of the needle 25 cushion alone.

Referring to the drawing by reference numerals, 6 designates a box-shaped base or chest having its rear wall extended upwardly as 7 and provided at the rear side 30 of its top with a horizontal wire 8 having its ends secured at 9 and its body spaced from the wall and formed with a series of upwardly projecting loops 10 upon which the regular button hole twist 11 of different 35 colors may be conveniently hung in the manner shown in Fig. 3.

Secured to the front side of the top of wall 7 is a box 12 divided into any desired 40 number of compartments 13, for holding basting cotton, sewing silk and linen threads of different colors.

In the rear portion of the base 6 I provide several compartments 14 for holding gimp for button holes, of different colors. In the 45 front end of the base I place a removable

needle cushion 15 which is removable by lifting it upward, since it is retained between the front end wall 6^a of the base and the front ends of two wooden strips or partitions 16, which extend rearwardly to the rear wall 7 and are secured to and by vertical cleats 17, which are secured to the sides of the box and form pockets 18 which are very handy for holding the usual flat cakes of tailor's chalk of different colors.

The cushion 15 is formed of wooden strips 19, 20, 21 forming a channel whose open top is covered by a strip of felt 15 having its edges secured to the base 19 by tacks 22. The covering felt forms a good cushion for 60 needles and pins to be placed as 23 in Fig. 5. The middle space 24 of the base is used for keeping thimbles, buttons, scissors and any other articles and tools useful on a tailor's table.

What I claim is:

1. A tailor's kit comprising a hollow base open at the top and having its rear wall extended a considerable distance above the base, a series of compartments open at the 70 top along the front of the upper end of said rear wall, and a wire spaced from the rear side of the top of the wall and secured with its ends to the wall.

2. The structure specified in claim 1, said 75 wire having a series of arches formed along its body.

3. The structure specified in claim 1, and a series of compartments along the inner side of the lower end of said rear wall.

4. The structure specified in claim 3, and a removable needle cushion along the inner side of the front wall of the base, and a series of narrow pockets along each side wall of the base, extending from the rear wall to 85 said cushion which is thereby held in its place.

In testimony whereof I affix my signature.

LORENCE ERICKSON.
